(57) **CLAIM**

The ornamental design for a multipurpose detection device,
as shown and described.

DESCRIPTION

This application is related to U.S. Design patent application Ser. No. 29/164,398, entitled “A Multipurpose Detection Device,” filed on the even date hereof, which is expressly incorporated herein in its entirety by reference thereto.

FIG. 1 is a front view of a first embodiment of a multipurpose detection device showing my new design;

FIG. 2 is a rear view thereof;

FIG. 3 is a right side view thereof;

FIG. 4 is a left side view thereof;

FIG. 5 is a top view thereof;

FIG. 6 is a bottom view thereof;

FIG. 7 is a perspective view thereof;

FIG. 8 is a front view of a second embodiment of a multipurpose detection device showing my new design;

FIG. 9 is a rear view thereof;

FIG. 10 is a right side view thereof;

FIG. 11 is a left side view thereof;

FIG. 12 is a top view thereof;

FIG. 13 is a bottom view thereof; and,

FIG. 14 is a perspective view thereof.
